UNITED STATES PATENT OFFICE.

ELMER J. JONES, OF DENVER, COLORADO.

DEVICE FOR REGISTERING WOOD-BASE CUTS ON PRINTING-PRESSES.

SPECIFICATION forming part of Letters Patent No. 728,723, dated May 19, 1903.

Application filed June 20, 1902. Serial No. 112,477. (No model.)

To all whom it may concern:

Be it known that I, ELMER J. JONES, a citizen of the United States, residing at Denver, in the county of Arapahoe and State of Colorado, have invented certain new and useful Improvements in Devices for Registering Wood-Base Cuts on Printing-PresSES; and I do declare the following to be a full, clear, and exact description of my invention, such as will enable others skilled in the art to which it appertains to make and use the same, reference being had to the accompanying drawings, forming a part of this specification, in which similar letters of reference indicate corresponding parts in all the figures.

My invention relates to a device for registering wood-base cuts on printing-presSES, especially adapted for registering color-plates where several impressions are to be run in different colors of ink.

The objects of my invention are to provide a register for cuts that will facilitate the use of the cuts as they come from the factory mounted upon a wood base; one that will dispense with the remounting of the cuts on metal bases or expensive patented bases; one that makes a light form for the press, and hence one that can be run at a greater speed than when the forms are heavy, as is the case when metal bases are used; one that can be very quickly adjusted, also one that provides efficient means for successfully registering the cuts at any desired angle; one that obviates the necessity of unlocking the forms to register the cuts; one in which every cut is entirely separate from other cuts placed within the same chase; one which dispenses with the flexibility of the form, and one which can be adjusted to fit any-sized cut in a very short space of time.

The foregoing objects are attained by the construction illustrated in the drawings, in which—

Figure 1 is a perspective view of a form mounted within a chase embodying my invention. Fig. 2 is a view of one of the corner-plates. Fig. 3 is an isometrical view of one of the registering devices. Fig. 4 is a modified view of same.

In further referring to the drawings, A represents an ordinary chase used in locking up any kind of a form.

B represents a wood-base cut of ordinary construction.

C indicates the registering devices, one of which is placed in a position to operate against each corner of the cut. These registering devices are constructed of right-angled parts, as illustrated. Each part has a recess or depression, (represented by C¹ in the different figures of the drawings.) An internally-threaded aperture is provided through these corner parts from the recessed portion, in which operates an externally-threaded thumb-screw, (represented by C² in the different figures of the drawings.) The registering devices C are provided with offsets C⁴ on their inner surfaces and the internally-threaded apertures pass through the offsets, which afford a greater bearing-surface for the thumb-screws C² and operate to strengthen the construction and prevent the stripping of the threads. The thumb-screws are beveled or conical-shaped on the end of the screw portion. The heads of the thumb-screws are provided with numerous recesses or depressions, (indicated by C³.) facilitating their adjustment by means of the insertion into such depressions of some flat instrument or tool especially constructed for the purpose.

D represents corner-plates bent to form right angles, as fully illustrated in Fig. 2 of the drawings. These corner-plates are adapted to be placed around the corners of the cuts and to provide a metal base for receiving the thrust of the beveled or conical points of the thumb-screws C², as will be made manifest by consulting Fig. 1 of the drawings.

E represents ordinary furniture used in locking up the form.

F represents furniture used in properly spacing the registering devices, so that they can be adjusted to fit any-sized cut.

G represents the lockable quoin used in locking up forms; but I do not claim anything thereon, as they are covered by prior Letters Patent and do not form a part of the subject-matter of this application.

The material from which my new registering devices are constructed is any suitable metal, either bronze, brass, or steel, as I do not confine myself to any one metal nor to any one manner of constructing the device, but desire to cover by Letters Patent the

principle involved and construct it according to the most practical plans without deviating from the principle illustrated and claimed.

The successful operation of my invention 5 will be very readily comprehended by consulting Fig. 1. The form is locked up in the ordinary manner and the registering devices spaced to fit the cut by means of the furniture, (represented by F.) The cut is then 10 placed within the space provided therefor, and by means of the thumb-screws C', provided in the registering device C, the cut can be registered in the very finest possible manner, the corner-plates first being placed 15 around the corners of the cuts against which the conical or beveled points of the thumb-screws operate.

Having thus described the nature and objects of my invention with the manner of constructing and applying the same, what I claim as new, and desire to secure by Letters Patent of the United States, is—

1. The combination within a chase with the usual furniture, of a work-registering device 25 comprising a block having a recess formed therein and internally-threaded apertures connecting the recesses with the periphery of the block, integral adjustable means received within the apertures and recesses, the inner 30 ends of the adjusting means contained entirely within the periphery of the block, the opposite ends of the adjusting means extending through the apertures and outside of the block and adapted to engage the work to be 35 registered.

2. The combination within a chase, with the usual furniture, of a device for registering the work relative to the chase, the device comprising a plurality of angled movable 40 blocks located at and embracing the corners of the work, bearings formed in the blocks, adjusting-screws carried by the blocks, the heads of the screws located entirely within the peripheries of the blocks, the screws received 45 and operating in the bearings in the blocks and angled plates received upon the corners of the work, the inner ends of the screws bearing against the plates.

3. The combination within a chase, with the 50 usual furniture, of a work-registering device comprising a plurality of suitably-formed blocks adapted to embrace the corners of the work, the blocks having recesses formed therein and internally-threaded apertures connecting the recesses with the inner peripheries of the blocks, screws operating within the apertures and recesses, the screws adapted to move longitudinally relative to the blocks, the heads 55 of the screws provided with means for permitting the rotation thereof, and plates, the contours of which correspond to the shape of the

blocks, the plates adapted to embrace and rest upon the corners of the work to be centered.

4. In a device for registering cuts, the combination with a chase and furniture, of angled 65 blocks having recesses formed therein, screws operating within the recesses, and angle-plates located around the corners of the cut to be registered, the plates adapted to receive the end thrust of the screws which bear thereagainst, 70 the heads of the screws having depressions formed therein for facilitating the use of an instrument in the adjustment of the screws.

5. In a device for registering cuts, the combination with a chase and form comprising 75 suitable furniture and locking devices, of registering devices consisting of right-angled blocks having recesses formed therein, screws operating within the recesses, and corner-plates located at the corners of the cut to receive the end thrust of the screws. 80

6. In a device for registering cuts, the combination with blocks having apertures therein, screws received and operating in the apertures, the blocks locked up within a suitable 85 chase by means of ordinary furniture and locking devices with the cut to be registered, and movable plates located against the sides or edges of the cut and adapted to receive the thrust of the screws. 90

7. The combination within a chase, with suitable furniture, of a registering device comprising a plurality of movable blocks having recesses formed therein and screw-threaded apertures connecting the recesses with the inner 95 peripheries of the blocks, of adjusting-screws received within the recesses and apertures, the screws movable longitudinally with relation to the blocks and plates of similar form as the blocks, the plates adapted to embrace the corners of the cut to be registered, the screws provided with conical inner ends which bear against the plates to effect the adjustment of the cut, the blocks being entirely independent of the chase. 100

8. In a device for registering wood-base cuts, the combination with movable angled blocks having recesses formed therein, thumb-screws operating in the recesses, the blocks locked up within a suitable chase by means 110 of ordinary furniture and locking devices, the cut to be registered provided with movable corner-plates adapted to receive the thrust of the ends of the thumb-screws, the blocks being independent of the chase. 115

In testimony that I claim the foregoing as my own I hereunto subscribe my name in the presence of two witnesses.

ELMER J. JONES.
